CLOTHES-WASHING MACHINE

Donald K. Ferris, Dayton, Ohio, assignor to General Motors Corporation, Dayton, Ohio, a corporation of Delaware

Application April 3, 1944, Serial No. 529,331

4 Claims. (Cl. 68—131)

1

This invention relates to clothes washing machines and more particularly to washing machines.

An object of this invention is to improve the washing action of a washing machine of the type in which an agitator is vertically reciprocated, by improving its construction and operation.

Another object of this invention is to improve the washing action in a washing machine, in which the agitator is vertically reciprocated, in such a manner as to reduce and minimize the tangling of clothes during the washing action.

Another object of this invention is to improve the washing action, in a washing machine of the type in which the agitator is vertically reciprocated, by reducing the speed differential of the agitator near one limit of its reciprocation as compared to the speed differential near the other limit or as compared to that produced by a simple crank and connecting rod, more specifically this reduction in speed differential taking place near the lower limit of the reciprocation. By speed differential is meant the change in deceleration and acceleration which occurs as the agitator approaches and passes beyond its lower limit of reciprocation.

The washing action of my improved washing machine is characterized by the fact that the major portion of the clothes being washed are caused to float in the upper part of the body of liquid with only a minor portion of the clothes being circulated in the lower part of the body of washing liquid, this floating action allowing the clothes to untangle themselves as the washing action progresses, so that any article of clothing may be freely lifted out in an untangled condition, with very little effort. This improvement, I believe, is due to the fact that the agitator is moved quickly towards the bottom of the tub, thus producing a very violent ejection of water radially from between the agitator and the bottom of the tub. As the agitator reaches its lower limit of reciprocation, its speed differential is reduced materially (below the normal speed differential in the motion of the usual crank and connecting rod of the same amplitude), and this delaying or dwelling action permits the violently ejected water to propel the clothes away from the agitator and towards the surface of the main body of washing liquid before the agitator begins its fast upward motion. This action causes the clothes to unspiral and untangle themselves as they float near the surface of the liquid.

2

In addition, because of the specific embodiments used to accomplish the foregoing purposes and objects, this invention provides a construction, in the vertical reciprocating agitator type of washing machine, which prevents breakage due to unyielding objects, such as buttons or the like. This advantage is obtained because of the yielding connection between the agitator and the driving mechanism.

Further objects and advantages of the present invention will be apparent from the following description, reference being had to the accompanying drawings, wherein a preferred form of the present invention is clearly shown.

15 In the drawings:

Fig. 1 is a vertical cross-sectional view of a washing machine embodying features of my invention;

Fig. 2 is a reciprocation curve corresponding to the agitator motion in Fig. 1;

Fig. 3 shows the rim portion of an agitator similar to that shown on Fig. 1, but slightly modified;

Fig. 4 is a vertical cross-sectional view of a slightly different embodiment from that shown in Fig. 1;

Fig. 5 is a reciprocation curve of the agitator and eccentric, produced by the embodiment shown in Fig. 4.

30 A washing machine which embodies the foregoing principles of my invention may include a tub having a cylindrical side wall 10a and a rounded bottom wall 11a. These walls are adapted to contain a main body of washing liquid.

35 This body of liquid, with the clothes to be washed, preferably should be at a level indicated by the dotted line 12a, while the agitator 13a is stationary, which assumes an upper surface substantially as indicated by the dotted line 14a, 40 while the agitator is reciprocating. The clothes or the like, which are to be washed, are placed in the main body of liquid within the tub.

The agitator 13a preferably is a small, rigid, cone-shaped, downwardly directed agitator, 45 which has imparted thereto a series of relatively short reciprocations having a relatively fast downward stroke and a delaying action at the lower limit of said reciprocations. Reciprocations of this character, when they are imparted to an

50 agitator, reciprocating near the bottom of the tub, substantially as illustrated, produce an improved turbulent action in the main body of liquid of such a character as to cause the main portion of clothes to float apparently near the surface of the main body of liquid, while a gradual

55

toroidal action is imparted to the main body. However, this motion so distributes the clothes within the main body of liquid, that any one article of clothing may be removed from the main body of liquid with very little effort. Practically no effort is required to untangle it from the other articles of clothing. This action is distinguished from that produced by an agitator which has motion imparted to it by the usual crank and connecting rod, by the fact that the mass of clothes are not formed into a compact ring-like mass near the agitator and are not spiralled and wrapped around each other as is the case with an agitator having the usual crank and connecting rod drive.

The reason for this improved washing action, I now believe, is due to the fact that the agitator is moved downwardly at an increased speed (as compared to motion imparted by the usual crank and connecting rod) until it is near the bottom of the tub. This produces a violent radial ejection of liquid which propels any articles of clothing which may be near the bottom of the tub, violently away from the agitator and upwardly to near the surface of the liquid. The delaying or dwelling action of the agitator near its lower limit of reciprocation permits the liquid ejection to propel the clothes substantially away from the agitator before the agitator begins the rapid portion of its upward stroke.

The washing machine may include a supporting structure such as legs 25a, cylindrical apron 26a, and a cross channel member 27a. This supporting structure may support the tub 10a by means of a rubber-like ring 28a at the upper end of apron 26a. The channel 27a may support an upwardly extending ring 29a which is secured to a central opening 30a in the bottom of the tub. A flexible bellows 31 may be secured to the ring 29 by a wire ring 32a and may extend upwardly and may be secured to a disc 33a on the plunger 53.

By way of example, the tub 10a may be 23" in diameter and 18" in height from its lowest portion near the opening 30a to its highest portion at the rim 35a. The agitator may have a cone-shaped bottom 13ma at 45 degrees to the horizontal, and may be 10" in diameter at the bead 36a. The cylindrical body 13na, at the upper portion of the agitator, may be 3" in diameter. The bead 36a, at the lower portion of the agitator, may be spaced from $\frac{5}{8}$ " to $\frac{3}{4}$ " above the bottom of the tub, when the agitator is at its lowest position, and the reciprocation may have an amplitude of $2\frac{1}{4}$ ". The shaft 50 may be rotated approximately at 280 revolutions per minute and may be provided with a counterbalancing flywheel (not shown) of sufficient weight to insure substantially uniform rotation of shaft 50.

With the foregoing dimensions, the machine operates most satisfactorily with approximately 6 lbs. (dry weight) of clothes, and with approximately 18 gallons of water in the tub.

This type of motion imparts an increased turbulence to the liquid and clothes, and the clothes can be seen to be freely suspended in the water, and readily separable from each other. The amount of agitation is very pronounced in proportion to the power consumed as compared to an agitator which is reciprocated by the usual crank or eccentric and connecting rod.

If desired, the lower portion of the rigid cone of the agitator may be provided with a flexible edge 45 instead of the rigid bead 36, as shown in Fig. 3.

The shaft 50 drives a circular eccentric cam 51, connecting rod 52, plunger 53 and supporting rod 54. The plunger 53 reciprocates in a bearing structure 11a supported on the channel member 27a. A disc 55 is fixed to the rod 54. Two springs 56 and 57 bear against the disc 55, surround the rod 54, and also bear against the rings 58 and 59 which are secured to the agitator 13a, and are slidably supported on the rod 54. When the shaft 50 is rotated at uniform speed, by a motor and flywheel, not shown, the rod 54 produces substantially a harmonic curve as indicated at 60 in Fig. 2. This substantially harmonic motion is imparted to the center of the spring structure 56, 57. The spring structure 56, 57 causes the agitator 13a to lag behind in its reciprocation and to produce the curve 61 of Fig. 2. The portions 62 of curve 60 indicate the down-strokes of the rod 54 while the portions 63 indicate its up-strokes. Likewise the portions 64 of the curve 61 indicate the down-strokes of agitator 13a, while the portions 65 indicate its up-strokes. Because of the reaction of the cone 13ma, and the bottom wall 11a of the tub, in trapping the liquid, the agitator has a slower acceleration and deceleration (speed differential) near the lower limit of its reciprocation than the substantially harmonic motion of the usual crank or eccentric and connecting rod drive and is also materially slower than the motion near its upper limit of reciprocation. This is indicated, respectively, by the gentle curves 66 at the lower limits of curve 61 and by the sharp curves 67 at the upper limit of the reciprocation.

The springs 56 and 57 have a coefficient of compression of 60 lbs. per lineal inch, and each spring is initially compressed 1", so that each spring exerts a push of 60 lbs. on the washers 58 and 59 respectively, while the agitator is stationary. The agitator 13a may have a weight of 2.4 lbs. and the cam 51, which preferably is rotated at 280 R. P. M., may impart a total amplitude of $1\frac{1}{4}$ " to the rod 54. When the tub is filled with 18 gallons of water and 6 lbs. (dry weight) of clothes, the reactions of the weight of the agitator, resistance of the water and the like, causes the agitator to lag behind the reciprocation of the rod 54 and to have a reciprocation amplitude of about $2\frac{1}{4}$ ", as indicated by the curve 61 in Fig. 2.

Because of the resilient connection between the agitator 13a and driving mechanism 51, no breakage is likely to occur if a large button or the like should become lodged under the agitator.

In the modification shown in Fig. 4, the tub is provided with side and bottom walls 10b, 11b and is filled to level 12b with a body of washing liquid, which has an upper surface 14b when the agitator 13b is reciprocated. The washing machine is provided with a supporting structure 25b, 26b, 27b, 28b, 29b, opening 30b, flexible bellows 31b, wire ring 32b and plate 33b, all substantially the same as the corresponding parts in Fig. 1. In Fig. 4, however, the agitator 13b is reciprocated by a different mechanism, which produces substantially the same type of reciprocation as heretofore described with respect to Fig. 1. This includes a rotatable shaft 70, carried in bearings rigidly mounted on the supporting structure of the washing machine, and driven by a motor and flywheel, not shown. The shaft 70 drives a circular eccentric cam 71, connecting rod 72 and reciprocating plunger 73, which reciprocates in the stationary bearing structure 11b. The connecting rod 72 is connected to the plunger 73 by

the pin 74. The plunger 73 has fixed thereto end rings 75 and 76. Supporting rod 77 is slidably mounted on the ring 75 and in the upper bearing structure 78 of the ring 76. A ring 79 is fixed on the rod 77. Springs 80 and 81 are placed between the ring 79 and the rings 75 and 76 respectively. These springs each have a coefficient of compression of 60 lbs. per lineal inch, and each spring is initially compressed 1", so that each spring exerts a push of 60 lbs. on the rings 75 and 76 respectively, while the agitator is stationary. The agitator 13b may have a weight of 2.4 lbs. and the cam 71, which preferably is rotated at 280 R. P. M., may impart a total amplitude of 1 1/4" to the plunger 73. When the tub is filled with 18 gallons of water and 6 lbs. (dry weight) of clothes, the reactions of the weight of the agitator, resistance of the water and the like, causes the agitator to lag behind the reciprocation of the plunger 73 and to have an amplitude of about 2 1/4".

The reciprocation curve of plunger 73 is indicated at 90 in Fig. 5. The spring structure 80 and 81, causes the agitator to produce the curve 91. The portions 92 of curve 90 indicate the down-strokes of the plunger 73, while the portions 93 indicate its up-strokes. Likewise the portions 94 of the curve 91 indicate the down-strokes of the agitator 13b, while the portions 95 indicate its up-strokes. Because of the reaction of the cone 13mb, and the bottom wall 11b of the tub, in trapping the liquid, the agitator has a slower acceleration and deceleration (speed differential) near the lower limit of its reciprocation than the substantially harmonic motion of the usual crank or eccentric and connecting rod and is also materially slower than the motion near its upper limit of reciprocation. This is indicated, respectively, by the gentle curves 96 at the lower limits of the curve 90 and by the sharp curves 97 at the upper limit.

In the modification shown in Figs. 4 and 5, the size of the tub and the agitator are substantially the same as in Fig. 1. Accidental breakage, by buttons or the like, is also prevented in this modification by the resilient connection between the agitator and driving mechanism.

If desired, the lower portion of the agitator of Fig. 4 may be provided with a flexible cone edge 45 instead of the bead 36b, as indicated in Fig. 3.

While the forms of the invention as herein disclosed, constitute preferred forms, it is to be understood that other forms might be adopted, as may come within the scope of the claims which follow.

What is claimed is as follows:

1. Apparatus of the character described comprising a tub having side and bottom walls adapted to contain a body of washing fluid and clothes, an agitator mounted for vertical reciprocatory movement in the central portion of said tub close to its bottom wall, said agitator being small relative to said tub and being substantially cone-shaped with the large end of the cone directed downwardly, and means to impart short, rapid, vertical reciprocations to said agitator with a motion delayed near the lower limit of the reciprocations to a greater extent than the motion produced by the usual crank and connecting rod drive, said means including mechanism to produce short, rapid, reciprocatory motion with a greater dwell at the lower limit of reciprocation than at the upper limit and a lost-motion resilient device actuated by said mechanism to reciprocate said agitator, and said device having

movably supported means actuated by said mechanism, driven means connected to said agitator and actuated by said movably supported means, and resilient means interconnecting said movably supported means and said driven means to give flexibility to the reciprocatory movement of said agitator.

2. Apparatus of the character described comprising a tub having side and bottom walls 10 adapted to contain a body of washing fluid and clothes, an agitator mounted for vertical reciprocatory movement in the central portion of said tub close to its bottom wall, said agitator being small relative to said tub and being substantially 15 cone-shaped with the large end of the cone directed downwardly, and means to impart short, rapid, vertical reciprocations to said agitator with a motion delayed near the lower limit of the reciprocations to a greater extent than the motion 20 produced by the usual crank and connecting rod drive, said means including mechanism to produce reciprocatory motion of the usual crank and connecting rod type with a greater dwell at the lower limit of reciprocation than at 25 the upper limit, and a lost-motion resilient device for transmitting the motion produced by said mechanism to said agitator and for modifying it, and said device having movably supported 30 means connected to said mechanism, driven means connected to said agitator and movable relative to said movably supported means, and resilient means interconnecting said movably supported means and said driven means for moving said driven means flexibly relative to said 35 movably supported means.

3. Apparatus of the character described comprising a tub having side and bottom walls adapted to contain a body of washing fluid and clothes, an agitator mounted for vertical reciprocatory movement in the central portion of said tub close to its bottom wall, said agitator being small relative to said tub and being substantially cone-shape with the large end of the cone directed downwardly, and means to impart short, rapid, vertical reciprocations to said agitator with a motion delayed near the lower limit of the reciprocations to a greater extent than the motion produced by the usual crank and connecting rod drive, said means including mechanism to produce reciprocatory motion of the usual crank and connecting rod type with a greater dwell at the lower limit of reciprocation than at the upper limit, and a lost-motion resilient device for transmitting the motion produced by said mechanism 45 to said agitator and for modifying it, and said device having slidably supported means connected to said mechanism, driven means connected to said agitator and extending slidably in said slidably supported means, and resilient means under compression interconnecting said slidably supported means and said driven means for moving said driven means flexibly relative to said slidably supported means and thereby rendering the reciprocatory movement of said agitator flexible.

4. Apparatus of the character described comprising a tub having side and bottom walls adapted to contain a body of washing fluid and clothes, an agitator mounted for vertical reciprocatory movement in the central portion of said tub close to its bottom wall, said agitator being small relative to said tub and being substantially cone-shaped with the large end of the cone directed downwardly, and means to impart short, rapid, vertical reciprocations to said agitator with a motion delayed near the lower limit of the re-

reciprocations to a greater extent than the motion produced by the usual crank and connecting rod drive, said means including mechanism to produce reciprocatory motion of the usual crank and connecting rod type with a greater dwell at the lower limit of reciprocation than at the upper limit, and a lost-motion resilient device for transmitting the motion produced by said mechanism to said agitator and for modifying it, and said device having a movably supported means connected to and actuated by said mechanism, driven means fixed to said agitator and movable relative to said movably supported means, and a plurality of resilient means interconnecting said movably supported means and said driven means for moving said agitator resiliently both upwardly and downwardly.
